BED AND CYLINDER ADDRESS PRINTING MACHINE

Harmon P. Elliott, Watertown, Mass.

Application April 22, 1950, Serial No. 157,445

2 Claims. (Cl. 101—56)

1

This invention relates to improvements in printing machines of the general type wherein the printing is effected from printing devices, such as stencils, which may be advanced in succession to a printing position. More particularly it relates to mechanism for controlling the movements of a printing member so that stencil advance occurs during one movement of the printing member while the member is held out of printing relation to the stencils, and printing occurs during subsequent movement of the printing member while the member is in printing relation to an advanced and stationary stencil.

It is among the objects of the invention to provide a printing machine wherein a printing member has a circuitous path of travel during each printing cycle whereby it comes into printing coaction with a printing device only during a portion of each cycle of its circuitous travel.

Another object is to provide a printing machine wherein a printing member has circuitous travel during each cycle of its movements, with means holding it elevated above the plane of printing during its travel along one substantial portion of its circuitous path and holding it in the plane of printing during its travel along another substantial portion of its circuitous path.

A further object is to provide a printing machine which is capable of being bodily lifted by hand following each printing and placed as desired for a second printing, and wherein a handle is manually operable in one direction to advance a printing device to a printing position and is manually operable in the reverse direction to effect a printing from the printing device in the printing position.

It is, moreover, my purpose and object generally to improve printing machines and especially printing machines wherein printing is effected from printing devices which are advanced in succession to a printing position.

In the accompanying drawings:

Fig. 1 is a top plan view of the printing machine embodying features of the invention;

Fig. 2 is a plan view of a series of stencils in end to end relation;

Fig. 3 is a side elevation of the printing machine of Fig. 1;

Fig. 4 is a cross-sectional view on line 4—4 of Fig. 3, on a larger scale;

Fig. 5 is a cross-sectional view on line 5—5 of Fig. 4;

Fig. 6 is a cross-sectional view on line 6—6 of Fig. 3, on the scale of Figs. 4 and 5; and

Fig. 7 is a top plan view of a stencil, on the scale of Figs. 4—6.

2

Referring to the drawings, the invention is illustrated as it may be embodied in a portable, manually operable printing machine wherein stencils, or comparable printing devices, move in succession to and through a printing position in response to manual actuations of a lever which also effects a printing from the printing device which at any time is in the printing position. It should be understood, however, that features of the invention are applicable to printing machines in general, whether manually or automatically operable, for controlling the movements of the coacting printing members between which printing elements move in succession to a printing position.

The illustrated machine has two spaced apart parallel rails 10, 12 which together provide a track along which stencils 14, or the like, may be moved in succession from a stencil holder 16 at one end portion of the track to a stencil holder 18 into which the stencils deliver at the opposite end portion of the track. The stencil holders 16, 18 are arranged over the space between the rails 10, 12, and they are secured to the rails, as by screws 20, whereby they maintain the predetermined proper spacing and parallelism of the rails.

The adjacent side edges of the rails 10, 12 are grooved at 11 and 13, respectively, for receiving the opposite side margins of the stencils 14. A supply stack of the stencils will be held in stencil holder 16 with the lower stencil of the stack resting on the rails 10, 12, the upper walls of whose edge grooves 11, 13 are cut away at 22 so that the lowermost stencil rests on the bottom walls of the grooves as shown in Fig. 6. Hence, the lowermost stencil is in position to engage in the rail grooves, in a well known manner, when moved along the track.

Stencil holder 18, at the other end of the track, receives stencils delivering to it from the track, the upper walls of the rail grooves 11, 13 being cut away at 24 and there being a raised portion 26 on each rail whereby the lowermost stencil in holder 18 rests on these elevations 26, thereby providing space between it and the rails into which the delivering stencil may enter and lift the stack of stencils in moving to its position at the bottom of the stack, as is well known in the art.

A printing mechanism indicated generally at 30, is mounted on rails 10, 12 between the stencil holders 16, 18. As best seen in Figs. 4 and 5, the printing mechanism comprises a relatively large ink roll 32 and a smaller ink roll 34, both mounted on and between the spaced parallel legs 36, 38

of an actuator which is indicated generally at 40. The actuator is pivotally mounted on a fixed rod 42 which extends between and is supported by the brackets 44, 46 rising respectively from the rails 10 and 12. The upper portion of the actuator has a hand grip 41 thereon facilitating manual actuations of the actuator about the axis of rod 42, and has an arm 48 fixed thereon and extending down to a location a little above the rail 12. One end of a link 50 is pivotally connected to the lower end of arm 48 as at 52, and the other end of the link is pivotally connected at 54 to a stencil pusher member 56 whose pusher portion 57 is adapted to engage the end edge of the lowermost stencil in holder 16 and push it, and the stencils ahead of it in the track, one stencil length along the track when actuator 40 is actuated counter-clockwise as in Fig. 3. A guide rod 58 on pusher 56 slidably engages in guide 60 to maintain the pusher portion 57 in proper alignment with a stencil.

Ink roll 32 has an absorbent surface which is capable of holding a considerable supply of ink. It is fixed on a shaft 62 which extends loosely through slots 64, 66 in actuator legs 36, 38, one end of shaft 62 projecting loosely through an opening 68 in bracket 44, with a finger knob 70 on its outer end, and the other end of shaft 62 terminating short of the other bracket 46. Roll 32 may be manually rotated by knob 70 to bring different portions of its surface into position for ink-transferring coaction with roll 34.

The smaller ink roll 34 is fixed on a shaft 72 which extends loosely through the deep notches 74, 76 in the end portions of actuator legs 36, 38, and coil springs 78 constantly bias the two roll shafts 62, 72 toward each other thereby to maintain the surface of roll 32 in ink-receiving contact with roll 34. Two other coil springs 80 constantly bias roll shaft 72 toward the inner ends of the notches 74, 76. However, according to the invention, each end of roll shaft 72 engages in a cam slot 82 of a cam plate 84 which is secured to the inside lower portion of each bracket 44, 46, and the springs 80 constantly bias the opposite ends of roll shaft 72 toward the upper walls of the cam slots 82.

Referring to Fig. 5, a cam-lever 86 is operable in each cam slot 82, being pivoted at one end at 88 to the adjacent bracket 44 or 46 and having a pin 87 at its other end portion extending loosely through a slot 90 in the bracket 44 or 46. A spring 92 biases each cam-lever 86 toward engagement with the upper wall of its cam slot 82, each spring 92 having one end anchored at 94 on the outer side of a bracket 44 or 46 and having its other end connected to the pin 87 of a cam-lever 86.

Each cam-lever 86 is shaped and positioned in its cam slot 82 to provide a horizontal race-way between the cam-lever and the lower wall of the slot when the cam-lever is in its position of Fig. 5, so that an end of roll shaft 72 can traverse the race-way from one end of the cam slot to the other end. The pivoted end of each lever is rounded and positioned centrally of the width of the cam slot and inward from the adjacent end of the cam slot, thereby to provide a curved continuation of the mentioned race-way leading around the pivoted end of the cam-lever to its upper side. Hence, an end of the roll shaft 72 can travel to the left along the under side of the cam-lever in Fig. 5 and around the pivoted end of the lever to its full line position in Fig. 5.

The upper side of each cam-lever 86 has a sub-

stantial portion, adjacent its pivoted end, which is parallel to its lower side and which is spaced from the upper wall of cam-slot 82 to provide a horizontal continuation of the mentioned race-way leading from the pivoted end of the cam-lever toward its other end, at the upper side of the lever. However, the upper side of the cam-lever, toward its biased end, has an inclined cam surface 96 in position to be engaged by the roll shaft 72 when moving to the right, in Fig. 5, along the upper portion of the cam race-way. As the shaft engages surface 96 and continues its movement to the right, it depresses the biased end of the cam-lever 86 and the cam-lever snaps back to its position of Fig. 5 as soon as shaft 72 passes beyond the biased end of the lever to its upper dotted position in Fig. 5 whence it can move downward to the lower horizontal portion of the race-way.

It will be apparent from the foregoing description that a counter-clockwise actuation of the actuator 40 in Figs. 3 and 5 will cause a stencil 14 to be advanced to printing position under the printing mechanism 30, assuming that this stencil will have been advanced previously one stencil length along the track from holder 16. During this advance of a stencil to printing position, roll shaft 72 will traverse the cam-slot 82 to the right along the upper side of the cam-lever 86 in Fig. 5, with the springs 80 holding the ends of shaft 72 against the upper wall of the cam groove. The lower ink roll 34, in consequence, moves in a generally horizontal path to the right in Fig. 5 and in substantially spaced relation to the advancing stencil 14. During the final travel of roll 34 to the right, its shaft 72 cams the biased ends of cam-levers 86 downward, and these levers snap back to their positions, as represented by the lever 86 in Fig. 5, as soon as the shaft 72 passes beyond the lever to the limit of its movement to the right, at which time the machine will be conditioned for a printing from the advanced stencil in response to a clockwise actuation of actuator 40.

Assuming that the machine has been placed on a support with a work sheet to be printed upon arranged between the support and the stencil which has been advanced to printing position, a clockwise actuation of the actuator 40 will cause the ends of roll shaft 72 to ride down the inclined biased end of the cam-lever 86 and into the lower horizontal portion of the cam race-way. This involves a tensioning of springs 80 which hold the ends of the shaft 72 against the lower sides of the cam-levers 86 with ink roll 34 lowered into coacting printing relation to the stencil 14 in the printing position. The roller 34 rolls to the left over the address-bearing tissue portion 15 of the stencil, in a manner to print the address from the stencil on the underlying work sheet before the ends of its shaft 72 ride up the curved portion of the race-way to the position of the shaft as shown in full lines in Fig. 5 wherein it is ready for another stencil advance in response to a counter-clockwise actuation of actuator 40.

The machine as herein disclosed is extremely light in weight and is adapted for convenient manual placement upon work sheets to be printed upon, followed by a back and forth actuation of the actuator 40 to effect a printing on each work sheet.

However, the herein disclosed mechanism for successively traversing one printing member toward another and for attaining printing coaction

between the printing members only on alternate traversing movements of said one printing member, is applicable generally to printing machines, whether manual or automatic, wherein it may be desirable to effect a printing in response to only alternate actuations of a printing member.

I claim as my invention:

1. A printing machine comprising a track along which printing devices may be moved in succession to a printing position, a printing roll operative at the printing position and having a shaft disposed transversely of the track and parallel to the plane of said printing devices, means for reciprocating the shaft and roll longitudinally of the track, and guide means engaging opposite ends of the roll shaft for guiding the reciprocating shaft through a circuitous path with the roll in printing relation to the printing device in the printing position during its movement in one longitudinal direction and out of printing relation with said printing device during its movement in the opposite longitudinal direction, said guide means comprising, at each end of the roll shaft, a fixed guide for engaging the end of the roll shaft and guiding the movement of the roll shaft in one direction along said track, and a cam-lever pivoted at one of its ends in spaced relation to said fixed guide and having its free end constantly biased toward engagement with said fixed guide and constituting a yieldable abutment in the path of movement of the end of the roll shaft in said one direction along the fixed guide, said biased end of the cam-lever having one cam surface arranged to be engaged by said end of the roll shaft moving in said one direction whereby the biased end of the cam-lever is cammed out of the path of the end of the roll shaft until said end of the roll shaft moves past the cam-lever, and having another cam surface on which said end of the roll shaft rides when the direction of movement of the roll is reversed thereby to guide said end of the roll shaft around the biased end of the cam-lever for travel in guided engagement with said cam-lever during the said reversed movement of the roll along said track.

2. A printing machine comprising a track along which printing devices may be moved in succession to a printing position, a printing roll operative at the printing position, actuating means

10 15 20 25 30 35 40 45 50

for operating said printing roll longitudinally of a printing device at the printing position, guide means for guiding each end of said roll in a circuitous path in response to actuations of said actuating means, said path at each end of the roll including spaced apart generally parallel straight portions along one of which an end of the roll has guided movement in one direction and along the other of which said end of the roll has guided movement in the opposite direction, said guide means including, at each end of the roll, a yieldable member constituting a yieldable obstruction at a predetermined location along said one parallel portion of said circuitous path, said yieldable member being adapted to yield when engaged by an end of the roll moving in one direction along said one parallel portion of the circuitous path, resilient means acting on said yieldable member for restoring it following a said yielding thereof, said yieldable member, when restored, barring any reverse travel of the end of the roll along said one parallel portion of the circuitous path while guiding said end of the roll to said other parallel portion of the circuitous path for reverse movement therealong, and means constantly biasing the opposite ends of the roll toward the plane of said one parallel portion of the circuitous path, said roll being out of printing relation to a printing device at the printing position when moving along said one parallel portion of the circuitous path and being in printing coaction with a printing device at the printing position when moving along said other parallel portion of the circuitous path.

HARMON P. ELLIOTT.
